(57) **CLAIM**

The ornamental design for a zipper tie, as shown and described.

DESCRIPTION

FIG. 1 is a left side elevational view of a zipper tie showing my design;

FIG. 2 is a right side elevational view thereof;

FIG. 3 is a bottom plan view thereof;

FIG. 4 is a top plan view thereof;

FIG. 5 is a front elevational view thereof;

FIG. 6 is a rear elevational view thereof;

FIG. 7 is a perspective view of the zipper tie with the tie in a curved position;

FIG. 8 is a perspective view of the zipper tie with the slider engaged with the tie; and,

FIG. 9 is a top plan view of the zipper tie with the slider engaged with the tie to enclose a bag.

The claimed article is shown broken away in FIGS. 1-4 and 7-9 to indicate indeterminate length. The phantom lines shown in the FIG. 9 are illustrative of environmental structure only and form no part of the claimed design.
